UNITED STATES PATENT OFFICE.

GEORGE ADAM WEBER, OF STAMFORD, CONNECTICUT, ASSIGNOR TO THE WEBER RAILWAY JOINT MANUFACTURING CO., OF NEW YORK, N. Y., A CORPORATION OF WEST VIRGINIA.

RAILROAD-RAIL JOINT.

SPECIFICATION forming part of Letters Patent No. 705,170, dated July 22, 1902.

Application filed November 30, 1901. Serial No. 84,214. (No model.)

To all whom it may concern:

Be it known that I, GEORGE ADAM WEBER, of Stamford, in the county of Fairfield, State of Connecticut, have invented a new and useful Improvement in Railroad-Rail Joints, of which the following is a specification.

I will describe a railroad-rail joint embodying my improvement and then point out the novel features in the claims.

10 In the accompanying drawings, Figure 1 is a transverse vertical section of a railroad-rail joint embodying my improvement, the plane of the section being intermediate of the ends of adjacent rail-sections. Fig. 2 is a similar 15 section showing the parts in somewhat-different relations. Fig. 3 is a transverse section of one of the parts of the joint.

Similar letters of reference designate corresponding parts in all the figures.

20 A' designates one of two adjacent railroad-rail sections arranged in line to form a portion of a track.

B designates an angle-chair having a base b', an upright b², and an angle-brace b³. This 25 chair is long enough to receive the adjacent end portions of the two rail-sections.

On one side of the rail-sections is a fish-plate C, preferably of the kind known as an angle fish-plate, having a base c', adapted to 30 fit upon one of the flanges forming the foot or base of the rail-sections, and an upright c², extending to the under side of the head of the rail-sections. Preferably this fish-plate will be of the same length as the chair B. On the 35 opposite side of the rail-sections is a fish-plate or channel-bar D, fitting snugly between the other flange comprised in the foot or base of the rail-sections and the opposite portion of the head of the rail-sections. Its upper and 40 lower edges d' d² are outwardly extended. Instead of making them continuous, like flanges, they may be made discontinuous in the form of lugs. As here shown, they diverge outwardly. Preferably this fish-plate 45 or channel-bar will be of the same length as the fish-plate C. Within the fish-plate or channel-bar D is a block E of wood or analogous packing material. Bolts F pass through the fish-plates C D, the webs of the rail-sections, the block E, and the upright of the 50 chair B.

The chair B and the fish-plates C and D

will preferably be made of steel. The block E is shown as fitting snugly against the outer vertical side of the fish-plate or channel-bar 55 D and against the surfaces of the outwardly-extending edges d' d² of said fish-plate or channel-bar D. That one of its surfaces which is adjacent to the upright of the chair B is, however, inclined so that it projects farther outwardly at the upper portion than at the lower portion. This is a structural feature of great practical importance in such a block of wood or similar compressible material, because it provides for drawing all the 60 parts firmly together in their proper relations without any tendency to displace the base of the chair relatively to the foot or base of the rail-sections.

Fig. 1 represents the base before the bolts 70 have been fully tightened, and Fig. 2 represents the base after the complete tightening of the bolts.

What I claim as new, and desire to secure by Letters Patent, is—

1. In a railroad-rail joint the combination 75 with rail-sections arranged in line, of a chair having a base and an upright, a fish-plate on one side, a fish-plate on the other side, a block of wood or similar compressible material fitting between the last-named fish-plate and the upright of the chair, and inclined downwardly away from the upright of the chair, and bolts for securing the parts together.

2. In a railroad-rail joint, the combination 85 with rail-sections arranged in line, of a chair having a base and an upright, a fish-plate on one side of the rail-sections, a fish-plate or channel-bar having outwardly-extended upper and lower edges arranged on the other 90 side of the rail-sections, a block of wood or similar compressible material fitting into the fish-plate or channel-bar last named and inclined downwardly away from the upright of the chair, and bolts for securing the parts together.

In testimony whereof I have signed my name to this specification in the presence of two subscribing witnesses.

GEORGE ADAM WEBER.
